[57] CLAIM

The ornamental design for a portable dental housing, as shown and described.

DESCRIPTION

FIG. 1 is a front elevational view of a portable dental housing showing our new design;

FIG. 2 is a left side elevational view thereof, the right side being a mirror image;

FIG. 3 is a top plan view thereof;

FIG. 4 is a bottom view thereof;

FIG. 5 is a rear elevational view thereof; and,

FIG. 6 is a top perspective view thereof, on a enlarged scale.
